DES. 2239

Thomas R. Evans of Philadelphia Penna.

Letters Patent No. 2239 Dated Jan'y 3, 1866

Design for the Quarter of a Balmoral Shoe.

The schedule referred to in these letters is filed and making part of the same.

To all whom it may concern,

Be it known that I Thomas R. Evans
of Philadelphia County of Philadelphia, State of Pennsyl-
vania, have invented or produced a new and original
design for the "quarter" of a "balmoral" shoe, and I do
hereby declare the accompanying Drawing with the follow-
ing explanation of the same to form a full, clear and
exact description of the said Design.

In the accompanying drawing I represent the
upper of a "balmoral" shoe, B being the "Toe" and C one
of the "quarters" which is of the ornamental form shown
in the drawing and is attached to the "wamp" between the
points V.V.

I claim the design for

The quarter C, of a "balmoral" shoe, of the ornamental form shown in the drawing.

In testimony whereof I have signed my name to
this specification in the presence of two subscribing
witnesses
